FRANK S. TRUMBULL, OF BRIDGEPORT, CONNECTICUT.

BULLET-CASTING MACHINE.

1,319,674.

Specification of Letters Patent. Patented Oct. 21, 1919.

Application filed September 28, 1918. Serial No. 256,034.

To all whom it may concern:

Be it known that I, THOMAS B. STEPHENSON, a citizen of the United States of America, residing at Forestville, Connecticut, 5 have invented a new and useful Bullet-Casting Machine, of which the following is a specification.

My invention relates to a bullet casting machine and machines of like nature. 10 The machine in question is of the type where the bullets are cast as objects dependent from or attached to a continuous rod or "gate", such objects being separated from the gate as the casting progresses.

15 The objects of the invention are to automatically dispose of the gate metal and to prevent loss or waste of the same.

Further objects of the invention are to render the operation of the machine continuous and automatic. 20

Briefly stated, the invention consists in returning the gate metal as fast as the cast objects are stripped therefrom to the casting pot which provides the supply of casting metal. The means for accomplishing this purpose consists in the present disclosure of transfer means in the form of a 25 guiding chute which takes the cast rod after the objects are stripped therefrom and redirects the same back into the casting pot. The separation or stripping of the objects from the gate rod is shown accomplished by means of a stripper blade which engages the cast rod as it emerges from the 30 traveling mold mechanism, which stripper is provided with a guide for directing the rod away from the mold and into the transfer chute.

Other features of the invention will appear as the specification proceeds. 40

The accompanying drawing illustrates the invention embodied in a simple, practical form, it being understood that the form of the invention is susceptible of modification 45 without departure from the true spirit and scope of the invention.

In this drawing:

Figure 1, is a side view of the machine with parts broken away and shown in section. 50

Fig. 2 is a broken plan view taken substantially on the plane of line 2-2 of Fig. 1.

Fig. 3 is a broken sectional view taken

substantially on the plane of line 3-3 of 55 Fig. 1.

In the machine illustrated the traveling mold mechanism is made up of a pair of endless chains 5, carrying matching mold sections 6 formed to provide a continuous 60 casting channel 7 with casting chambers 8 communicating therewith. The product of this traveling mold is a rod or gate 9, with bullets 10 or other objects dependent therefrom. 65

The mold chains are each supported on suitable sprockets 11, one or more of which may be driven as by means of a drive shaft 12 and suitable gearing 13.

14 designates the casting or melting pot 70 provided with a nozzle 15 discharging into the open casting channel. A dam 16 is shown supported in this casting channel in rear of the nozzle to prevent the molten metal from flowing backwardly. 75

The flow of metal may be adjusted as by means of a valve 17 so that the flow will be such that in the forward movement of the traveling molds the rod with the attached objects will be cast and advanced 80 through the machine.

At the discharge end of the machine, where the mold sections separate, due to the passage of the chains around the respective sprockets, there is located, in the present 85 disclosure the means for stripping the dependent objects and separating the rod from the mold. This means is shown in the form of a cutter blade 18 having a sharpened cutting edge entered in the open casting channel substantially at the point of commencement of the separating movement of the chains and adapted to sever the objects in the casting chambers from the rod in the casting channel. The upper surface 90 of this stripper blade is shown formed on an upward incline and curved to form a guide 19 for curling or bending the rod upward out of the plane of the casting mechanism. 95

20 designates a chute for guiding and transferring the stripped rod back to the casting pot. This chute is preferably formed on a gradual curve so as to reverse the movement of the gate rod on an easy 100 or gradual curve.

To facilitate the movement of the rod through the return guide, I have shown a

conveyer in the form of a sprocket chain 21 working in the guide chute and bearing on the rod so as to conform the rod to said chute and to advance the rod therethrough.

5 The entrance end of the return guide is disposed adjacent the guiding portion of the cutter so as to take the bent rod therefrom and said guide extends rearwardly to a point where it will deliver the stripped 10 rod back into the casting pot.

In the operation of the machine, the molten metal flows from the casting pot into the traveling mold mechanism where it congeals and travels forwardly with said mold 15 mechanism in the form of a rod with objects dependent therefrom. At the discharge end of the machine the cutter blade strips the dependent objects from the rod and deflects the rod upwardly into the reverse conveyer 20 which carries the stripped rod back into the melting pot. The stripped objects discharge into a suitable collection receptacle 22 and the rod is immediately remelted into material for further casting. The operation 25 therefore, is thus a continuous one and there is no waste as the gate material is immediately remelted, practically before it has time to entirely cool, into fresh casting material.

The cutter blade 18 may be adjustably 30 supported so that it can be brought into proper relation to the casting channel in which it is designed to fit. For this reason, I have shown the blade as pivotally supported at 23 so that it may be rocked or 35 tilted and thus raised or lowered in the casting channel, the blade being secured in the adjusted position as by means of a clamp nut 24.

I claim:—

40 1. In a machine of the character described, the combination with traveling mold mechanism for forming a cast rod with objects dependent therefrom, of means for stripping said objects from the cast rod and 45 means for automatically remelting the stripped rod as it is advanced by the traveling mold mechanism.

2. In a machine of the character described, the combination of traveling mold 50 mechanism for casting a continuous rod with objects dependent therefrom, means for stripping said objects from the cast rod, a melting pot and means for delivering the stripped rod advanced by the traveling mold 55 into said melting pot.

3. In a machine of the character described, the combination of traveling mold sections for casting a continuous rod with objects dependent therefrom, a pot for delivering the molten material to said mold 60 sections, means for stripping the objects from the cast rod and means for returning the stripped rod back to the casting pot.

4. In combination, a casting pot, traveling 65 mold mechanism for casting a rod with ob-

jects dependent therefrom, means for stripping said objects from the cast rod, and a guide chute receiving the stripped rod and arranged to deliver the same back into the casting pot.

5. In a combination like that set forth in claim 4, a conveyer operating on the stripped rod in the guide chute for assisting in returning the same to the casting pot.

6. Traveling mold mechanism having a 75 channel and chambers in communication therewith for casting a rod with objects dependent therefrom, a stripper blade entered in said channel for separating the objects from the cast rod and a guide carried by 80 said stripper for directing the stripped rod away from the traveling mold mechanism.

7. Traveling mold mechanism having a channel and chambers in communication therewith for casting a rod with objects dependent therefrom, a stripper blade entered in said channel for separating the objects from the cast rod, a guide carried by said stripper for directing the stripped rod away from the traveling mold mechanism, and 90 means for guiding the rod directed by said stripper back to the casting end of the traveling mold mechanism.

8. In a machine of the character described, traveling mold mechanism having a casting 95 end and a discharge end and arranged to cast a continuous rod with objects dependent therefrom, means at the discharge end for stripping the objects from the cast rod and means for returning the stripped rod back 100 to the casting end of the machine.

9. In combination, a casting pot, traveling mold chains receiving material therefrom and arranged to form a continuous cast rod with objects dependent therefrom, a stripper 105 for separating the objects from the cast rod, a guide associated with said stripper for directing the stripped rod back to the casting pot and a conveyer for advancing the stripped rod along said guide.

10. In combination, traveling mold chains having a casting channel and communicating chambers for casting a continuous rod with objects dependent therefrom, a stripper blade entered in said channel for separating the objects from the cast rod, a curved guide on said stripper blade for directing the rod away from the mold chains and guiding means receiving the rod from said stripper blade.

11. In a casting machine, the combination with means including a casting pot and traveling mold mechanism for casting a gate element with dependent objects, means for separating said objects from the cast gate 125 element and means for automatically returning the gate element as the objects are stripped therefrom to the casting pot.

12. In combination with means for forming a continuous cast rod with dependent ob-

jects, means for stripping said objects from the cast rod and means for melting the stripped rod as the objects are separated therefrom.

5 13. In combination with means for forming a continuous cast rod with dependent objects, means for stripping said objects from the cast rod and means for automatically returning the metal of said stripped 10 rod to the casting means.

14. In combination with traveling mold mechanism for casting a rod with objects dependent therefrom and a casting pot for delivering the molten metal to said traveling 15 mold mechanism, means for stripping the objects from the cast rod and means for bending the rod away from the traveling mold mechanism and returning the same to the casting pot.

20 15. The herein described process of feeding molten material from a casting pot to a traveling mold mechanism to form a continuous rod with objects dependent therefrom, stripping said objects from the rod as

25 it is cast and returning said rod as it is stripped and substantially while still warm from the casting operation back into the casting pot.

30 16. In a casting machine, means for casting a continuous rod with elements depending therefrom at intervals, a guide for said rod and a cutter for cutting off said elements adjacent thereto.

35 17. In a casting machine, two chains having parallel stretches, mold elements carried by said chains having channels at their meeting edges and communicating chambers.

for casting a rod with attached objects, a guide for the cast product in line therewith and means for automatically cutting off the 40 objects from the cast rod.

18. In a casting machine, coöperating oppositely disposed mold blocks having opposed recesses forming a continuous channel and mold chambers in communication with 45 the channel thus formed, means for supplying the casting material into the continuous channel to thereby produce a rod with the objects formed in the mold chambers connected therewith, means for advancing the 50 coöperating mold blocks past the supply point and for separating the coöperating mold blocks at a point beyond the point of supply to thereby carry the cast continuous rod with the dependent objects free of 55 the mold blocks, guiding means disposed in line with and receiving the cast product issuing from between the mold blocks, and means for separating the objects from the rod by which they are carried free of the 60 mold blocks.

19. In a casting machine, movable mold elements, chambered to form a continuous rod with objects connected therewith, means for supplying the casting material to the 65 chambered mold elements, means for advancing the mold elements past the point of supply to thereby advance the rod and connected objects carried thereby, a guide receiving the cast product thus advanced, and 70 means adjacent said guide for separating the objects from the cast supporting rod.

THOMAS B. STEPHENSON.
